UNITED STATES PATENT OFFICE

2,120,879

LAMP SOCKET

Frank Wear and Alexander K. Whyte, Toronto,
Ontario, Canada, assignors to General Electric
Company, a corporation of New York

Application August 31, 1937, Serial No. 161,766
In Canada December 24, 1936

3 Claims. (Cl. 173—328)

Our invention relates to lamp sockets, and more particularly to sockets adapted for use with tubular lamps of the type having a separable contact cap at each end.

5 An object of our invention is to provide a socket which may be readily manufactured and assembled at a low cost.

A further object of our invention is to provide a socket capable of accommodating lamps of both 10 large and small diameters, and further adapted for both flush and surface mounting.

Another object of our invention is to provide a socket of the type specified with a readily assembled terminal cover, the cover and contact 15 terminal being arranged to permit easy wiring in different positions, and to permit through wiring if desired.

Another object of our invention is to provide a socket readily adaptable to all methods of mounting the lamps of the character described, and 20 one which is simple in construction and serves to readily connect a lamp in circuit and to hold the lamp securely in position.

What we consider to be novel and our invention 25 will be better understood by reference to the following specification and appended claims when considered in connection with the accompanying drawing in which

Fig. 1 is a view of a tubular lamp mounted in a 30 pair of sockets of our invention.

Fig. 2 is an exploded perspective view of a socket.

Fig. 3 is a sectional view of the socket.

Fig. 4 is a plan view of the terminal cover, and

35 Fig. 5 is a view illustrating the flush mounting of the socket of our invention.

Referring to the drawing 10 indicates a tubular lamp of cylindrical shape having a filament 11 extending from end to end and connected at 40 each end to a ferrule (not shown). To connect lamp 10 in an electrical circuit, contact caps 12 are provided at each end which separably engage the ferrule in the end of the lamp, as is now known in the art, and which are adapted to cooperate with the sockets 13 of our invention, each cap having projecting spring finger contacts 12a which engage the contact clip in the socket thus connecting the ferrule at the end of the lamp to the socket contact clip.

45 Socket 13 comprises a body 14 L-shaped in cross section, of molded insulating material, the leg 15 of which is formed with a substantially rectangular opening 16 therethrough, and the foot 17 of which is provided with a threaded aperture 18 therethrough. The upper end of leg 15

is curved to cooperate with the contour of the contact cap 12, and the sides thereof are given a taper 19 adjacent the end, for the purpose of allowing a large size tubular lamp the full amount of lateral movement. A substantially U-shaped metallic contact clip 20, designed to always give an inward tension is adapted to fit within the opening 16 in leg 15, and the bottom of the clip is provided with an integral lateral extension 21 through which a terminal screw 22 is threaded 5 in a suitable threaded aperture formed therein. The bottom face of the foot 17 is suitably recessed as at 23 to accommodate the extension 21 on contact clip 20. The clip is secured in the opening 16 by means of a sheet of fibrous insulating 10 material 25 secured to the body 14 by suitable screws 26 entered in threaded holes in the bottom face of foot 17. The insulating sheet 25 is apertured as at 27 to permit access to the terminal screw 22, and the bottom face of foot 17 is cut 15 away or recessed as at 28 to accommodate the sheet 25.

In Fig. 4 we have shown a terminal cover or box 30 formed of molded insulating material and adapted to be secured to the bottom face of the 20 body 14. The cover 30 is shaped to conform generally with the conformation of the foot 17 of body 14, but extends laterally therebeyond adjacent the lower end of the leg 16. Rectangular bosses 31 extend upwardly from these lateral extensions and are spaced apart the width of the body 14. The cover 30 is provided with a through aperture 32 arranged to register with the threaded aperture 18 in foot 17, whereby a suitable screw 32a may be employed to secure 35 the cover 30 to the body 14. An aperture 33 extends through each of the rectangular bosses 31 for the reception of suitable screws or bolts for securing the cover 30 and body 14 to a supporting surface. The cover is formed hollow 40 interiorly and the side walls thereof are formed thin at portions thereof to provide knockouts 34 for the reception of the circuit wire or wires connected to the terminal screw 22.

In Fig. 5 we have illustrated the flush mounting of the socket of our invention through a sheet of facing material 35 in which a rectangular aperture is cut to accommodate the leg 15 of body 14. The socket is secured in position by means of a screw 36 arranged to pass through 45 an aperture in the facing 35 and to engage the threaded aperture 18 in foot 17. For surface mounting it will be understood that the socket of our invention may be secured to the supporting surface by means of screws 37 (Fig. 1) pass- 50 55

ing through the openings in the bosses 31 of cover 30. The circuit wiring is illustrated in Fig. 5 by the wires 38 passing through the knock-outs 34.

- 5 It will be observed that, as illustrated in the drawing the body 14 and cover 30 are formed to provide a substantially flat rear surface 40. This feature of the socket of our invention is useful, when two of the sockets are mounted back 10 to back to permit the abutted mounting of successive lamps. Moreover the taper on the upper end of leg 15 and the length of the leg permits the employment of this socket with tubular lamps of varying diameters. When the sockets are flush 15 mounted the securing screw is hidden beneath the lamp when the lamps are mounted in the socket.

While we have disclosed herein a particular embodiment of the socket of our invention we 20 do not wish to be limited thereto, but aim in the appended claims to cover all such modifications as fall within the true spirit and scope of our invention.

What we claim as new and desire to secure by 25 Letters Patent of the United States is:

1. A socket for use with tubular lamps which 30 comprises a substantially L-shaped body of insulating material having a rectangular aperture extending through the leg thereof, a metallic contact 35 clip fitted within said aperture and having an integral laterally extending portion arranged to abut the bottom of said body, means for connecting said clip to an electrical circuit, a sheet of insulating material secured to the bottom of said body arranged to hold said clip in said aperture and having an aperture therethrough permitting access to said connecting means, and a terminal cover box secured to the lower face of the foot of said body and having 40 portions thereof extending upwardly adjacent the lower end of said leg.

2. A socket for use with tubular lamps which 45 comprises an L-shaped body of insulating material having a leg and a foot, said leg extending a substantial distance above the upper surface of said foot and having a rectangular aperture extending upwardly therethrough, said foot having a threaded aperture therethrough, a metallic contact clip fitted within said rectangular aperture and having an integral laterally extending portion engaging the bottom surface of said foot, a terminal screw threaded in said laterally extending portion whereby said clip may be connected to an electrical circuit, a sheet of insulating 50 material secured to the bottom surface of

said foot and having an aperture therein whereby said sheet secures said clip against said body while affording access to said terminal screw through said aperture, a terminal cover box having a vertically extending aperture therethrough registering with said threaded aperture in said foot, said box having laterally and upwardly extending portions arranged to fit against the sides of said body adjacent the lower end of said leg, and means extending through the aperture in said box and engaging the threaded aperture in said foot for securing said box against the bottom surface of said body. 5

3. A socket for use with tubular lamps which 10 comprises an L-shaped body of insulating material having a leg and a foot, said leg extending a substantial distance above the upper surface of said foot and having a rectangular aperture extending upwardly therethrough, said foot having a threaded aperture therethrough, a metallic contact clip fitted within said rectangular aperture and having an integral laterally extending portion engaging the bottom surface of said foot, a terminal screw threaded in said laterally extending portion whereby said clip may 15 be connected to an electrical circuit, a sheet of insulating material secured to the bottom surface of said foot and having an aperture therein whereby said sheet secures said clip against said body while affording access to said terminal screw through said aperture, a terminal cover box having a vertically extending aperture therethrough registering with said threaded aperture in said box having laterally and upwardly extending portions arranged to fit against the sides of said body adjacent the lower end of said leg, and means extending through the aperture in said box and engaging the threaded aperture in said foot for securing said box against the bottom surface of said body, said body and said box 20 being formed with a flat side, said box having side walls formed thin at a plurality of points whereby the material thereof may be broken away at said points to form wiring channels, said laterally and upwardly extending portions of said box having apertures therethrough whereby said socket may be secured to a supporting surface by means of a pair of screws, and said threaded aperture in said foot providing means whereby said socket may be secured beneath a facing material by means of a screw engaging in said threaded aperture. 25
